CABINET HANDLE

Andi Aré, Palo Alto, and Eric Allen Inhelder, Mountain View, Calif., assignors to Hewlett-Packard Company, Palo Alto, Calif., a corporation of California

Filed Nov. 29, 1961, Ser. No. 67,742

Term of patent 14 years

(Cl. D10—8)

Fig. 1

Fig. 2

The sides and rear of the handle grip not shown are plain and unornamented.

The fragmentary portion of a panel shown in broken lines in FIGURES 1 and 2 is included for illustrative purposes only.

We claim:

The ornamental design for a cabinet handle, as shown and described.
